UNITED STATES PATENT OFFICE.

EZECHIEL WEINTRAUB, OF SCHENECTADY, NEW YORK, ASSIGNOR TO GENERAL ELECTRIC COMPANY, A CORPORATION OF NEW YORK.

VAPOR ELECTRIC APPARATUS AND METHOD OF OPERATING THE SAME.

1,086,105.

Specification of Letters Patent.

Patented Feb. 3, 1914.

Application filed November 17, 1902. Serial No. 131,636.

To all whom it may concern:

Be it known that I, EZECHIEL WEINTRAUB, a subject of the Czar of Russia, residing at Schenectady, county of Schenectady, State 5 of New York, have invented certain new and useful Improvements in Vapor Electric Apparatus and Methods of Operating the Same, of which the following is a specification.

10 My invention relates to improvements in that type of apparatus in which an electric discharge is produced within an exhausted envelop or in an envelop containing a more or less attenuated gas or vapor and comprises also certain methods of operating apparatus of the type indicated.

15 The features of novelty which characterize my invention I have set forth with particularity in the appended claims while the invention itself, as represented by some of the 20 various embodiments of which it is capable, is set forth, together with a description of its mode of operation, in the following specification which is to be taken in connection 25 with the accompanying drawings in which—

Figure 1 represents one embodiment of my invention, Fig. 2 a modification, and Fig. 3 still a different modification.

30 In the vapor electric lamp which I have chosen to illustrate my invention, the main electric discharge is produced between electrodes, one at least of which is of vaporizable material though it is within my invention to make all the main electrodes of vaporizable material. This electric discharge 35 I initiate in a novel manner. The starting of the main discharge is produced, in an electric lamp built in accordance with my invention, between two contact surfaces of 40 solid material such for example as graphite, iron, platinum, platinum-iridium, or similar solid and relatively non-vaporizable material. I recognize that nearly every substance under the action of an electric arc 45 or discharge may be to a certain extent disintegrated or vaporized, the effect of which is to give color or body to the discharge. By using the term vaporizable material I do not however intend to include substances 50 such as mentioned but rather such a class of substances as exemplified by mercury, potassium, sodium, caesium, rubidium, or combinations of any of these elements with mercury, or other substances of the same

general nature, which under electric action 55 are capable of vaporization to such an extent as to fill the envelop of the lamp with their vapor.

Having generated within the electric lamp a discharge between points or surfaces 60 of solid non-vaporizable material, which discharge takes place through the vapor of the vaporizable electrode or electrodes of the lamp, I transfer the seat of the discharge to the main electrodes, thereby putting the 65 lamp into normal operation. To effect this result I make one of the non-vaporizable electrodes either a part of one of the main electrodes or electrically connect it therewith. The initial discharge between the 70 solid contact points or surfaces I find under these circumstances creates a condition whereby the electro-motive force impressed upon the main electrodes of the tube is enabled to set up the normal discharge in the 75 lamp. I account for this fact on the hypothesis that the spark produced between the relatively non-vaporizable contacts ionizes the vapor of the vaporizable material in the lamp, which vapor is always present 80 even at ordinary temperatures, and this ionization is propagated along the tube or envelop until the space between the electrodes is wholly ionized, whereupon an arc or discharge takes place completely from 85 one main electrode to the other.

Although for the purpose of explaining my invention I have thus set forth very briefly the general nature of the phenomenon which I at present believe takes place, 90 I do not wish my invention to be confined by any particular theory of the matter, since whatever may be the theory, the benefits of my invention may be gained regardless of knowledge thereof.

95 In Fig. 1 which represents one embodiment of my invention, the main tube or light transmitting envelop of the lamp is indicated at 1. This envelop is represented in the form of a long, straight tube, but it will 100 be evident that the envelop may assume widely different forms without departing from my invention. The opposite ends of the tube are provided with main electrodes, one indicated at 2 consisting of a body of 105 artificial graphite, and the other, represented at 3, of some non-fluid vaporizable material such for example as an amalgam con-

taining a proportion of the substance mixed with the mercury to form the amalgam sufficient to render the amalgam non-fluid at ordinary temperatures. The upper electrode 2 which I have referred to as formed of artificial graphite is made of this material because of the fact, which I have discovered, that under the influence of the heat generated in the lamp during normal operation it does not disintegrate or give off vapors or gases. The graphite used may be either that produced in the electric furnace, in which all impurities which are vaporizable at the temperature of the electric furnace are driven off, or it may be natural graphite which has been purified by treatment under similar conditions.

The main electrode 2, for reasons presently to be set forth, is either flexibly or pivotally supported from the leading-in wire 4 by which current is conveyed to the electrode from some external source. This leading-in wire 4 may be jointed as indicated at 5. The lower electrode 3 is in turn provided with a leading-in wire 6 which passes through the lower end of the envelop 1 and extends up into and is surrounded by the body of the electrode 3.

To enable the lamp thus described to be started, I provide, in the present instance, an auxiliary or supplemental electrode 7 arranged so that it may make and break engagement with the main electrode 2. This auxiliary electrode may consist of a platinum or a platinum-iridium wire and is supported within a small tubular extension 8 of the main tube. This wire passes through the wall of this tubular extension at 9, and the external projection 10 thereof is connected either directly or through a suitably chosen resistance 11 to the other main terminal 6 of the lamp. The auxiliary electrode when in operation acts as a cathode and may therefore become highly heated, so that to equalize the heating of the tubular extension when the wire 7 passes through the walls thereof, I surround the wire 7 with a body of mercury 12, and in order to prevent this mercury from forming a vaporizable electrode, of the lamp, I insulate it from the wire 7 by surrounding the wire to a sufficient height with a coating of glass 13.

In order to start the lamp it is only necessary to slightly shake the upper end thereof until the main contact 12 makes and breaks contact with the wire 7. Under these conditions an electric discharge is produced as the contact is broken and this electric discharge I find immediately operates to set up the main arc or discharge between the main terminals 2 and 3, these actions of course taking place under the influence of currents supplied to the lamp over leads 14, 15 connected to the terminals 4-6 thereof. After the main discharge is once started, the dis-

charge from the main electrode 2 to this auxiliary electrode ceases. However, to insure the interruption of current in the circuit including the auxiliary electrode, in case of accidental short-circuit or the like, I provide a cut-out having contacts 14' in said circuit adapted to be separated when a magnet 15' in one of the main leads of the lamp is energized by the starting of the lamp.

In the arrangement described in connection with Fig. 1 the auxiliary electrode co-operates with the positive electrode or anode and is electrically connected outside of the lamp envelop to the negative electrode or cathode. This arrangement may however be reversed without departing from the spirit of my invention and such an arrangement is shown in Fig. 2 in which an auxiliary electrode 16 co-operates with the negative electrode or cathode and is electrically connected outside of the tube through the circuit 18 with the positive electrode or anode 20. The auxiliary electrode, while it may contact directly with the vaporizable cathode 17, is in this case arranged to make contact with a solid non-vaporizable extension 20 thereof formed for example of platinum-iridium wire. This wire extends through the walls of the envelop 21 and forms the leading-in wire with which connection is made with the supply circuit at 22. Unlike the arrangement shown in Fig. 1 the auxiliary electrode is movable with respect to its co-operating electrode instead of fixed. Various constructions may be employed in this connection, as for example the one shown in Fig. 2 in which the electrode consists of a cylinder, plate, prism, or the like 23, loosely suspended from a support 24 of wire passing through the end of a tubular projection 25 forming part of the envelop of the lamp. The part of the wire 24 where it passes through the extension does not require to be coated with glass and this in turn surrounded with a body of mercury, since the auxiliary electrode in this instance, acting as an anode, does not become as highly heated as may be the case with the auxiliary electrode described in connection with Fig. 1.

The mode of operation of the embodiment of my invention last described is substantially the same in principle as the operation of the arrangement shown in Fig. 1. To start the lamp the auxiliary electrode 16 is caused to engage the extension or projection 20, electrically connected with the cathode 17, by shaking the lamp or otherwise, and the spark thus caused immediately produces an ionization of the vapor in the lamp, and this ionization, extending to the vaporizable material forming the body of the cathode 17, is strengthened by the new supply of ions derived therefrom, whereupon the ionization is propagated along the

interior of the envelop thereby setting up an arc or discharge between the main electrodes of the lamp. As soon as this takes place the current through the conductor 18 connected 5 to the auxiliary electrode is interrupted by a cut-out having circuit-breaking contacts 18' in the circuit of the conductor 18 and an actuating magnet 19' in the main circuit leading to the lamp. A resistance 27 is placed 10 in the circuit or conductor 18 but in case of envelopes or tubes of short length and relatively low electro-motive force the resistance may be of small value or entirely omitted. In Fig. 3 I have represented an arrangement 15 whereby the lamp shown in Fig. 2 may be rendered automatic in action. The construction of the lamp is the same as that of Fig. 2 and the corresponding parts are therefore similarly designated. There is however 20 provided in addition a small electro-magnet 28 in series with one of the incoming leads and this magnet is arranged so that when current is turned on to the lamp it attracts the auxiliary electrode 29 thereby separating 25 it from the coöperating extension 30 of the cathode 31 thus producing the auxiliary starting arc which sets the lamp in operation in the manner already described. The auxiliary electrode 29 in this case requires either 30 to be made of magnetic material or to have attached thereto a piece of magnetic material so as to be acted upon by the magnet 28. The operating surface of the auxiliary electrode, when the same is not constructed 35 wholly of magnetic material, may be made of artificial graphite and this same material may be used of course for the construction of the auxiliary electrode in either or both of the arrangements shown in Figs. 1 and 2.

40 While a lamp constructed in accordance with my invention may have its negative electrode or cathode formed of single elements such as mercury, potassium, sodium, caesium, and rubidium, without the admixture of other material, I find it a decided advantage for various reasons to incorporate with low boiling point substances such as mercury, certain materials having a higher boiling point or vaporizing point whereby the 45 boiling point of the combination is rendered higher than the boiling point of the mercury or other substance alone due to which fact the vapor tension in the lamp is less for a given temperature when amalgams or mixtures of mercury with different substances are employed than when mercury alone is used. This reduction in the vapor tension of the lamp greatly increases the stability of operation of the same by which I mean 50 that the lamp is rendered less liable to be extinguished by fluctuations in the current supplied, in the external temperature, and so forth. It is to be observed however that the vapor tension in the lamp should not be 55 reduced too greatly by the means mentioned,

as otherwise the object desired may be defeated. Materials which I find of especial value for mixture with the mercury are those having a relatively low boiling point such for example as lithium and magnesium. 70

While I have described above in connection with the accompanying drawing various forms which my invention may assume, it is to be understood that numerous other changes and modifications may be utilized 75 without departing from the spirit of my invention and I therefore do not wish to be limited to the exact details shown and described.

What I claim as new and desire to secure 80 by Letters Patent of the United States is,

1. The method of operating a vapor electric apparatus, which consists in generating an electric discharge between a plurality of solid electrodes in the apparatus, and initiating thereby an electric discharge between electrodes, one at least of which is of vaporizable material. 85

2. The method of operating a vapor electric apparatus, which consists in maintaining the main electrodes of the lamp at different electric potentials, and causing an electric discharge to take place between said electrodes by first initiating an electric discharge between solid electrodes in the apparatus, one of which constitutes a portion or extension of one of the main electrodes. 90

3. The method of operating a vapor electric apparatus, which consists in impressing an electro-motive force upon the main electrodes of the apparatus, one at least of which is of vaporizable material, producing in said lamp an electric discharge between surfaces of relatively non-vaporizable material, and transferring the seat of the discharge 105 to the main electrodes.

4. The method of starting a vapor electric apparatus having electrodes, one at least of which is of vaporizable material, which consists in producing in the apparatus an electric discharge between electrodes of relatively non-vaporizable material, and transferring the seat of the discharge to the main electrodes. 110

5. The method of operating a vapor electric apparatus having a plurality of electrodes one at least of which is of vaporizable material, which consists in first ionizing residual vapor in the apparatus and then communicating the ionization to the vaporizable electrode. 115

6. The method of operating a vapor electric apparatus having electrodes one at least of which is adapted to emit vapor, which consists in maintaining electrodes of the apparatus at different potentials, ionizing residual vapor in the apparatus, and then generating ionized vapor from said vapor-emitting electrode. 125

7. In a vapor electric apparatus, the com- 130

bination of an envelop, and coöperating electrodes therein, one of said electrodes being formed of artificial graphite.

8. In a vapor electric apparatus, the combination of an envelop, a non-vaporizable anode, a vaporizable cathode, a solid non-vaporizable conductor projecting from the surface of the cathode, a supplemental or auxiliary anode coöperatively related to said projecting conductor, and means for producing an electric discharge between said supplemental or auxiliary anode and said projecting conductor.

9. In a vapor electric apparatus, the combination of an envelop, an electrode therefor

consisting of a body of readily vaporizable conducting material non-fluid at ordinary temperatures, a relatively refractory electrical conductor electrically connected to said body of vaporizable material, an auxiliary electrode or conductor adapted to make contact with said relatively refractory conducting body, and means for producing an electric discharge by breaking said contact. 20

In witness whereof, I have hereunto set 25
my hand this 15th day of November, 1902.

EZECHIEL WEINTRAUB.
